US00D639835S

(12) **United States Design Patent**
Martinez

(10) **Patent No.:** **US D639,835 S**
(45) **Date of Patent:** **** Jun. 14, 2011**

(54) **ANGLE WELDING ADAPTER**

(76) Inventor: **Leo Martinez**, Buena Park, CA (US)

(**) Term: **14 Years**

(21) Appl. No.: **29/370,791**

(22) Filed: **Sep. 7, 2010**

(51) **LOC (9) Cl.** **15-09**

(52) **U.S. Cl.** **D15/144**

(58) **Field of Classification Search** **D8/70, D8/71; D15/138, 144, 144.1, 144.2; 439/92, 439/105, 106, 108, 682, 685-687, 690, 692, 439/695, 696**

See application file for complete search history.

(57) **CLAIM**

The ornamental design for an angle welding adapter, as shown and described.

DESCRIPTION

FIG. 1 is a perspective view of my angle welding adapter;
FIG. 2 is a top plan in view thereof;
FIG. 3 is a rear elevational view thereof;
FIG. 4 is a right side elevational view thereof, it being understood that the left side elevational view is a mirror image thereof;
FIG. 5 is a front elevational view thereof;
FIG. 6 is a bottom plan view thereof; and,
FIG. 7 is a perspective view illustrating the manner of use of my invention.
